UNITED STATES PATENT OFFICE.

JOSEPH NATTERER, OF NEWARK, NEW JERSEY.

METALLIC MAT.

1,153,698.

Specification of Letters Patent. Patented Sept. 14, 1915.

Application filed April 21, 1915. Serial No. 22,743.

To all whom it may concern:

Be it known that I, JOSEPH NATTERER, a citizen of the United States, and a resident of Newark, in the county of Essex and State 5 of New Jersey, have invented certain new and useful Improvements in Metallic Mats, of which the following is a specification.

The invention relates to flexible metallic mats composed of a plurality of link members; and it has for its object to provide a 10 mat of this character of which the individual members thereof may be readily and inexpensively stamped from suitable metal and conveniently assembled to form the mat.

15 A further object of the invention is to so construct the mat that it may be manufactured in stock lengths from which any desired length of mat may be readily separated. The various links composing a mat, 20 furthermore, are designed to be securely interlocked without a separate rod or the like, as generally employed, and will permit of a neat finish at the sides and ends of the mat.

The nature of the invention will be best 25 understood when described in connection with the accompanying drawings, in which—

Figure 1 shows the improved mat in perspective. Fig. 2 is a detail plan of a number 30 of interlocked links. Figs. 3 and 4 are respectively a longitudinal and transverse section taken on the lines 3—3, and 4—4, Fig. 2. Fig. 5 is a plan of modification in the design of the links composing the mat.

Similar characters of reference designate 35 corresponding parts throughout the several views.

As shown in the drawings, the mat consists of a plurality of open ended links formed of strip metal and substantially in 40 the shape of a U with straight sides 11, Figs. 1 to 4; or, with straight sides and semi-circular, outwardly directed portions 12, Fig. 5, between the open and closed ends of a link. The longitudinally extending side 45 portions 11 are provided substantially at the middle portion of their free ends with circular perforations 13 forming pintle seats or bearings and with a slit or opening 14 extending thereto from an edge of the respective sides. These openings, when the links 50 are assembled to form the mat, are closed as will be hereinafter set forth. The laterally extending connecting portion or cross-bar 15 of a link is provided at each corner with 55 a pair of vertical slots 16 and 17 extending inwardly from the edges thereof and leav-

ing centrally located pintle portions 18 and 19. These portions are adapted to fit into the bearings 13 provided in the sides of fellow links, as shown more particularly in Fig. 3 of the drawings. When the slit 14 of such bearing is closed, the pintles 18 and 19 will be securely locked in the seats or bearings 13 provided in the sides of fellow links, as shown more particularly in Fig. 3 of the drawings, but will possess ample freedom of motion, effecting as it were a hinged connection between the link members but obviating the use of rods extending transversely through the mat for this purpose. 70

The interlocking arrangement, as shown in the drawing, is such that the links are spaced side by side in rows, the closed ends of a succeeding row being located between two adjacent links of the first row, one side 75 of each of said adjacent links being locked together by the end of a succeeding link. The desired width and length of the mat is obtained merely by adding links in both directions. To finish the mat at one end, suitable end pieces 20, which may be links with the sides cut off, are introduced over the ends of adjacent links, as shown. At the other end, the mat may be finished by merely including a cross-bar or piece 21, 80 which is notched for this purpose, being provided with corresponding pairs of vertical slots 22 affording intermediate portions 23, Fig. 1, adapted to be locked in the bearings of the various ends of the sides. In 85 this manner, the mat may be made in considerable lengths and from which other mats of various sizes may be separated by merely opening the links at any particular portion, inserting a bar and then closing the said 90 ends thereon. To finish the sides of the mat, it will be understood, of course, that only one side of a link member is required. The 95 ends and sides of the mat may, of course, be finished in any other suitable manner, 100 and the above described means afford, by way of example, one convenient means of effecting the same.

In Fig. 5, a modification in the form of the link is shown, a portion thereof, at the 105 closed end of the link, being rounded outwardly in order that said portions of adjacent links may contact and tend to reinforce each other to provide a more rigid structure. The links, whether rectangular or provided 110 with the circular portions 12, may be further strengthened, if desired, by means of

suitable rods 24 extending transversely through suitable perforations 25 provided in the sides of the link. In the case of the structure shown in Fig. 5, one end is thus finished by a rod 24, and the same may be applied to one end of the rectangular form shown in Figs. 1 to 4 and in which case the pieces 20 could be dispensed with. Or, both ends of the mat could thus be finished 10 by providing the perforations 25 sufficiently closed to the ends.

I claim:

1. A flexible, metallic mat composed of a plurality of interlocked U-shape links, the 15 two sides of a link having an outwardly curved portion between the open and closed ends thereof, said curved portions of adjacent links contacting with each other and the two sides of a link being pivotally held 20 in the ends of two succeeding links.

2. A flexible, metallic mat composed of a plurality of interlocked U-shape links, the two sides of a link being provided substantially at the middle of their free ends with 25 a bearing or pintle seat and with a corresponding slit extending thereto from an edge of the said sides, and the cross piece of a link being provided with two pairs of slots extending vertically inward from its two 30 edges to provide a central pintle portion adapted to be held in the said bearings of the sides to pivotally attach the links to one another and the entrance slits to said bearings being closed to lock the pintle portion 35 therein.

3. A flexible, metallic mat composed of a plurality of interlocked U-shape links, the two sides of a link being provided substantially at the middle of their free ends 40 with a bearing or pintle seat and with a corresponding slit extending thereto from an edge of the said sides, and the cross-piece of a link being provided with two pairs of slots extending vertically inward from its two 45 edges to provide a central pintle portion adapted to be held in the said bearings of the sides to pivotally attach the links to one another and the entrance slits to said bearings being closed to lock the pintle portion 50 therein, and a transverse bar adapted to be locked

in the bearings of said ends of the last row of links.

4. A flexible, metallic mat composed of a plurality of interlocked U-shape links, the two sides of a link being provided substantially at the middle of their free ends with 55 a bearing or pintle seat and with a corresponding slit extending thereto from an edge of the said sides, and the cross piece of a link being provided with two pairs of slots extending vertically inward from its two edges to provide a central pintle portion adapted to be held in the said bearings of the sides to pivotally attach the links to one another and the entrance slits to said bearings being 60 closed to lock the pintle portion therein, and a transverse bar provided with pairs of slots extending vertically inward from its edges to provide a central portion adapted to be locked in the bearings in said ends of the 65 last row of links.

5. A flexible, metallic mat composed of a plurality of interlocked U-shape links, the two sides of a link being provided substantially at the middle of their free ends with 75 a bearing or pintle seat and with a corresponding slit extending thereto from an edge of the said sides, and the cross piece of a link being provided with two pairs of slots extending vertically inward from its two 80 edges to provide a central pintle portion adapted to be held in the said bearings of the sides to pivotally attach the links to one another and the entrance slits to said bearings being closed to lock the pintle portion 85 therein, a transverse bar provided with pairs of slots extending vertically inward from its edges to provide a central portion adapted to be locked in the bearings in said ends of the last row of links, and side pieces consisting of a half of a link and attached to alternate rows of links at the side of the mat to finish the same.

Signed at Newark, in the county of Essex, and State of New Jersey, this 17th day of April, A. D. 1915.

JOSEPH NATTERER.
